EUGENE N. SITTON, OF LA FRANCE, SOUTH CAROLINA

PADDING WITH SELVEDGE

Application filed May 20, 1929. Serial No. 364,593.

The object of my invention is to provide padding for use on ironing machines which has a novel form of selvedge, whereby it may be wrapped around the roller of the ironing machine more smoothly than would otherwise be possible.

I attain these and other objects of my invention by the means illustrated in the accompanying drawings, in which,—

10 Figure 1 is a front elevation of a portion of padding illustrating my selvedged edge and showing the weave of the padding;

Fig. 2 is a detail sectional view on line 2—2 of Fig. 1;

15 Fig. 3 is a detail sectional view on line 3—3 of Fig. 1;

Fig. 4 is a detail sectional view on line 4—4 of Fig. 1; and

20 Fig. 5 is a view of three strands of the padding detached from each other to more clearly show the disposition of the respective strands of the warp and woof.

Like numerals designate like strands of threads in each of the several views.

25 Referring to the accompanying drawings, I provide three sets of weft strands 9, 11 and 13 as shown in detached relation in Fig. 5 of the drawings, which strands are crossed by the warp threads 6, 7 and 8, leaving a portion near the end of the padding through which no warp threads extend, as shown in each of the figures of the drawings. At the loop ends of the respective weft strands 9, 11 and 13 there is formed the loops 10, 12 and 14, respectively, as shown in Figs. 5 and 1 of the drawings and through these loops there extends the single stout warp thread or cord 5 to form a loop selvedge with the unwoven lengths 1 of the respective weft threads 11 and 13 extending between the single warp thread 5 and the warp threads 6, 7 and 8, which occur in the main body of the fabric, thus leaving the portion between the loop selvedge and the main body of the padding which is comparatively light, fluffy and more compressible than the main body of the padding, thus permitting of more evenly and advantageously rolling the padding around the ironing machine, as there is no abrupt end portion of the padding, the loop selvedge construction caus-

ing the padding to taper in thickness near and at the end of the fabric. The weave of the padding is a multiple ply plain weave, as shown in detail in Figs. 2, 3 and 4 of the drawings.

55 What I claim is:

1. A padding for use on the rollers of ironing machines comprising a thickly woven padding formed of warp threads, a plurality of weft strands arranged one over the other with a plain weave, said strands having an end portion of substantial length through which no warp threads cross to provide an end portion of less thickness than the main body of the padding, the ends of the respective weft threads each being looped, and having a single warp strand extending through said loop.

60 2. A padding for use on the rollers of ironing machines comprising a thickly woven padding formed of warp threads, a plurality of weft strands arranged one over the other, said strands having an end portion of substantial length through which no warp threads cross to provide an end portion of less thickness than the main body of the padding, the ends of the respective strands each being looped and having a warp strand extending through said loop.

65 3. The process of weaving a padding for use on ironing machines consisting in weaving the main body of the padding with a series of two or more overlying weft strands with warp threads, discontinuing the weaving of warp threads at a substantial distance from the ends of the respective ends of the weft strands, looping the ends of the respective weft strands, and threading a single warp thread or cord through the looped ends of the weft strands to provide a loop selvedge, 70 substantially as and for the purposes described in the foregoing specification.
